INHIBITION OF SPECIFIC NAPHTHYLAMIDE HYDROLYZING ENZYMES (LEUCINE AMINOPEPTIDASE) WITH DETOXIFIED SNAKE SERUM

Van B. Philpot, Jr., 161 State St.,
Framingham, Mass. 01701No Drawing. Filed Sept. 8, 1964, Ser. No. 395,015
4 Claims. (Cl. 195—103.5)

The present invention relates to inhibition or neutralization of proteolytic enzymes and more particularly to a means and method of inhibiting or neutralizing a proteolytic, naphthylamide hydrolyzing enzyme which is present in living organisms.

Much biological research is now concerned with the identification of enzymes and their role in diseases of the body. Such research is often complicated by difficulties in identifying and, in some cases, finding methods of inhibiting or neutralizing the enzymes being studied. Often enzymes are identified by their reaction with certain diagnostic test agents. For example, it is known that certain proteolytic enzymes hydrolyze naphthylamide and such enzymes may at least be partially identified by reaction with naphthylamide. In certain cases the presence or absence of particular enzymes can indicate the presence or absence of diseases of the body.

Accordingly it is an important object of this invention to provide a means and method for inhibiting or neutralizing certain proteolytic enzymes.

It is another important object of this invention to provide a method in accordance with the preceding object which permits at least partial identification of such inhibited enzymes and which method is useful in characterizing and identifying enzymes both in research and clinical diagnosis.

It has been found that certain naphthylamide hydrolyzing enzymes are present in the stomach tissue of humans who have gastric ulcers. Naphthylamide hydrolyzing enzymes are reported to be proteolytic and are referred to as leucine aminopeptidase in the New England Journal of Medicine at vol. 259, No. 10, page 469 (1958). The presence of such enzymes which are present at the ulcer site can ordinarily be determined by staining cryostat sections of an ulcerated stomach with a mixture of a naphthylamide and diazotized-o-aminoazotoluene. When such sections are made, the tissue surrounding the ulcer of the stomach wall stains an intense reddish violet color indicating the presence of proteolytic, hydrolytic enzymes. This intense reddish violet color does not result when tissues spaced from the ulcer site are stained. It is believed that the enzyme or enzymes which cause the reddish violet color upon staining are an etiological factor in the production of ulcers.

According to the method of this invention, the proteolytic naphthylamide hydrolyzing enzyme or enzymes causing the reddish violet color when stained, can be inhibited or neutralized by treating with detoxified snake serum. This method is useful as a research tool in understanding the mechanism of gastric ulcers and in characterizing and diagnosing the enzymes surrounding a gastric ulcer and perhaps others present in other diseased tissue. Thus, certain enzymes can be characterized as reacting with detoxified snake serum so that they do not give a red violet color when stained with a naphthylamide.

Preferably the snake serum used is detoxified by heating to form a precipitate therein and then removing the precipitate so that the snake serum will not destroy living human tissue. In the preferred method of this invention, a proteolytic, naphthylamide hydrolyzing enzyme present at the site of the human gastric ulcers in tissue closely surrounding such ulcers, is inhibited or neutralized by

2

treating an enzyme specimen with detoxified snake serum to cause a reaction between the enzyme and the snake serum. The reaction is preferably carried out at a temperature of from 20° to 37° C. for 15 min. to 1 hr. and causes the tissue containing the enzyme to show no red violet color change when stained with a naphthylamide.

The snake serum useful in the method of this invention is detoxified to the extent that it is nontoxic to living organisms and can even be injected into the body without causing tissue destruction and necrosis. Preferably detoxification is carried out by heating snake serum in test tubes in a water bath at 56° C. for 30 minutes. Following the heating step, a precipitation is formed within the snake serum which is dispersed in the serum and gives a milky appearance. This precipitate, which is capable of causing hemolysis in living organisms, is separated and removed from the treated serum preferably by filtering or centrifugation and decantation of the resultant clear, supernatant treated serum. The particular temperature at which the serum is heated may vary as may the time of heating so long as toxic materials in the serum are destroyed without destroying that portion of the serum which reacts with proteolytic naphthylamide hydrolyzing enzymes. Generally, heating occurs at temperatures of from about 45° C. to about 65° C. for from about five to about 90 minutes. The time and temperature may vary inversely with each other. In some cases temperatures above 65° C. may be used for shorter time periods. Conversely, temperatures below 45° C. may be used for longer time periods.

Rattlesnake serum is preferred for use in the method of this invention although other snake serums may be used and obtained from widely varying types of snakes including the Florida rattlesnake (*Crotalus adamanteus*), water moccasin (*Agkistrodon piscivorus*), Japanese habu (*Elaphe quadrivirgata*) and king snake (*Lampropeltis getulus*). The serum can be obtained in a conventional manner by cutting off a portion of the snake's tail and allowing the blood to flow into a sterile container. The serum is separated from the cells by centrifugation.

The particular naphthylamide indicator or test reagent used is preferably L-leucyl-B-naphthylamide in admixture with diazotized-o-aminoazotoluene. The L-leucyl-B-naphthylamide is a clear colorless liquid which can be hydrolyzed to a red or red violet color in the presence of certain proteolytic, hydrolytic enzymes or naphthylamide hydrolyzing enzymes such as leucine aminopeptidases which are reported to be proteases. The diazotized-o-aminoazotoluene serves to deepen and intensify the color change brought about by hydrolysis of the naphthylamide. In a preferred indicator solution of this invention, 30 milligrams of diazotized-o-aminoazotoluene along with 1 cc. of a 1% solution of L-leucyl-B-naphthylamide are mixed with 40 cc. of water and 10 cc. tris buffer pH 7.1.

In a specific example of this invention illustrating the inhibition or neutralization of certain proteolytic naphthylamide hydrolyzing enzymes by snake serum in accordance with this invention, a biopsy was performed on a living human and a stomach wall sample was obtained which was immediately frozen. Multiple cryostat sections were made of the stomach wall portion using a microtome and conventional procedures. The test tissue sections were placed on sample slides with two slides being made of a portion of each of the antrum, fundus and midportion of the stomach wall. The tissue on the two slides of the midportion of the stomach were adjacent the site of a gastric ulcer in the patient upon whom the biopsy was performed.

Each of the slides was air dried and one slide from each section of the antrum, fundus and midsection, respectively, was stained with the preferred naphthylamide indicator solution described previously by immersing the

slide for 4 hours at room temperature in a Copland jar filled with the staining solution. It was observed that the midportion section showed a very intense red violet color when viewed under the microscope. The tissue sections from the antrum and fundus not near the ulcer site did not show an intense red violet color but merely a red color. It is theorized that certain naphthylamide hydrolyzing enzymes are present in all sections, but, a specific naphthylamide hydrolyzing enzyme was present in the tissue surrounding the ulcer site which gave an intense red violet color change rather than merely a red color change with the naphthylamide. The enzyme or enzymes which gave the intense red violet color change are theorized to be etiological factors in producing ulcers.

A second set of slides carrying tissue sections from the antrum, fundus and midportion was treated by applying a few drops of detoxified snake serum to the tissue sections and incubating the slides for one hour at 37° C. The snake serum was rattlesnake serum which was heated in a test tube in a water bath at 56° C. for 30 minutes followed by centrifugation of the resulting precipitate and separation of the detoxified serum. After one hour of incubation, the slides were washed in gently running tap water and stained with the preferred naphthylamide solution as in the first series. Surprisingly it was found that a particular enzyme or enzymes which cause the deep red violet color in the stomach tissue surrounding the ulcer site was inhibited or neutralized by the snake serum since no red violet color was observed in the tissue section from the midportion in this procedure. In addition, the tissue sections from the antrum and fundus showed a red color as previously found in the first series.

When similar sets of slides are prepared from the same stomach specimen and treated with saline and human serum in place of snake serum, in accordance with the procedure followed for the second set of slides, the resultant stained color of each tissue section is substantially the same as obtained with the first series of slides. In some cases the human serum appears to intensify the red violet color in tissue specimens.

While a specific example of this invention has been described it will be obvious to those skilled in the art that many variations thereof are possible. For example, the specific incubation period for the test serum with the tissue specimen containing the proteolytic naphthylamide hydrolyzing enzyme can be varied. Similarly in some cases the enzyme may be reacted with the detoxified snake serum by mixture in a test tube with the enzyme in pure form removed from a tissue specimen. The snake serum

may be used in admixture with other enzymes or tissues containing such enzymes and then tested for a color change with naphthylamide to determine whether or not such enzymes are similar to or give similar reactions with snake serum as does the particular enzyme or enzymes surrounding a gastric ulcer site. The snake serum may be useful to inhibit or neutralize the proteolytic, naphthylamide hydrolyzing enzyme in other environments, and even therapeutically in living organisms. Other indicators can be used to test the presence or absence of a reaction between snake serum and an enzyme tested.

In view of the many variations possible, this invention is to be limited only by the spirit and scope of the appended claims.

- 15 What is claimed is:
1. A method of characterizing a proteolytic, naphthylamide hydrolyzing enzyme comprising detoxifying snake serum by heating said snake serum to a temperature in the range of from about 45° C. to 65° C.,
  - 20 applying said snake serum to said enzyme to form a mixture therewith, introducing a naphthylamide indication solution into said mixture, and observing the presence or absence of a red violet color with the presence of a red violet color indicating no inhibition of said enzyme and the absence of said red violet color indicating inhibition of said enzyme.
  - 25 2. A method in accordance with the method of claim 1 wherein said snake serum is rattlesnake serum.
  - 30 3. A method in accordance with the method of claim 1 wherein said snake serum is applied to said enzyme and incubated for at least 15 minutes at a temperature of at least 20° C.
  - 35 4. A method in accordance with the method of claim 1 wherein said naphthylamide is L-leucyl-B-naphthylamide and has diazotized-o-aminoazotoluene incorporated therewith.
